(57) CLAIM

The ornamental design for a knife sharpener, as shown and described.

DESCRIPTION

FIG. 1 is a front, right and bottom perspective view of a knife sharpener, showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and bottom perspective view of the knife sharpener in closed status thereof; and,

FIG. 10 is a rear, left and top perspective view of the knife sharpener in closed status thereof.

The broken lines shown in the drawings illustrate portions of the knife sharpener that form no part of the claimed design.
